UNITED STATES PATENT OFFICE.

MILTON H. SHOENBERG AND LESTER SCHON, OF SAN FRANCISCO, CALIFORNIA; SAID SCHON ASSIGNOR TO SAID SHOENBERG.

DESIGN FOR AN ELECTRIC CIGAR LIGHTER.

Application filed August 9, 1926. Serial No. 18,657. Term of patent 14 years.

To all whom it may concern:

Be it known that we, MILTON H. SHOENBERG and LESTER SCHON, citizens of the United States, and residents of the city and county of San Francisco, State of California, have invented a new, original, and ornamental Design for an Electric Cigar Lighter, of which the following is a specification, reference being had to the accompanying drawing, forming part thereof.

Fig. 1 of the drawing is a plan view of an electric cigar lighter embodying our design.

Fig. 2 is a side elevational view of a cigar lighter as shown in Fig. 1.

We claim:

The ornamental design for an electric cigar lighter substantially as shown.

MILTON H. SHOENBERG,
LESTER SCHON.
